[57] **CLAIM**

The ornamental design for a walk-in cabinet for radiation treatment of disease, substantially as shown and described.

DESCRIPTION

FIG. 1 is a front elevation of a walk-in cabinet for radiation treatment of disease, showing my new design; FIG. 2 is a side elevation of the same, as viewed from the left of FIG. 1.

FIG. 3 is a side elevation of the same, as viewed from the right of FIG. 1.

FIG. 4 is a rear elevation of the same, as viewed from the left of FIG. 2.

FIG. 5 is a top plan view of the same, as viewed from the top of FIG. 2.

FIG. 6 is a front elevation similar to FIG. 1 with the cabinet entrance doors in an open position.

FIG. 3

FIG. 2

FIG. 1

FIG. 6

FIG. 5

FIG. 4
